ELECTRICAL DEHYDRATOR HIGH VOLTAGE SUPPLY

Lyle Dillon, Los Angeles, Calif., assignor to Union Oil Company of California, Los Angeles, Calif., a corporation of California

Application September 2, 1932, Serial No. 631,534

4 Claims. (Cl. 204—24)

This invention relates to the art of disrupting emulsions and particularly to a high voltage supply means for petroleum emulsion dehydrators.

The object of this invention is to provide a means for supplying an interrupted and/or intermittent high voltage to an electrical dehydrator. It is also an object of this invention to provide a high voltage interrupted current of high intensity which will be effectual in breaking down low resistant emulsions which heretofore have required special treatment. A further object of this invention is to provide a process for supplying high voltage, high amperage current, either interrupted alternating, or interrupted direct current or both, at random, to an electrical dehydrator. A further object of this invention is to provide a high voltage supply for a dehydrator which shall be inherently free and protected from dehydrator short circuits and the attendant heavy demands. A further object is to provide an electrical supply, the current output of which shall be self regulating, and limited to a predetermined maximum, independently of treater operating conditions. A further object of this invention is to provide a petroleum dehydrator electrical supply with equipment of moderate capacity which will be capable of furnishing a current of sufficient intensity to maintain an effective treating potential gradient throughout a fluid of high conductivity. This process and apparatus is particularly adapted to the treatment of petroleum emulsions of the water-in-oil type which have low electrical resistances and poor dielectric properties.

Heretofore it has been difficult to efficiently dehydrate emulsions of high conductivity due to their short circuiting action in the treater. To prevent this short circuiting, dilution of the conductive emulsion with oil of higher resistance or of higher dielectric properties has been practiced. Even when such dilution is employed, intermittent heavy currents are drawn by short circuiting water chains which form between the electrodes of the treater. In order to protect the electrical system against these heavy currents, it has been necessary to connect into the electrical circuits, reactances, which together with the normal regulation of the transformer cause the said circuit to have a very pronounced drooping voltage regulation characteristic. Thus, when conductive emulsion comes between the electrodes, the current rises and the voltage correspondingly drops to a low ineffectual value at a time when a high voltage is most needed. To maintain an effective high voltage across such a low resistant

emulsion path, obviously would require a heavy current flow, one which a standard installation of normal capacity would be incapable of supplying.

This invention resides in a process and apparatus for subjecting petroleum emulsions to an interrupted and/or intermittent electrical potential. This invention further resides in a process and apparatus capable of supplying to a treater a momentary current of sufficient intensity to institute a momentary effective treating potential gradient throughout emulsions of high conductivity, without shortcircuiting or overloading the potential source. This invention further resides in a process and apparatus whereby a quantity of electricity is transferred from a source of electrical energy to the treater without at any time allowing the said source to be directly connected to the said treater.

This invention resides in processes and means for maintaining effective treater voltages under emulsion conditions, as outlined above, which would otherwise render the treater inoperative.

This invention further resides in processes and apparatus to accomplish the objects set forth hereinabove.

Other objects and advantages of the invention will be evident hereinafter.

The drawing diagrammatically illustrates one form of a process and apparatus embodying this invention.

Fig. 1 is a diagram of the apparatus and electrical connection.

Fig. 2 illustrates a momentary position of the interrupter of Fig. 1.

Fig. 3 illustrates a modification of Fig. 1 for operation of a plurality of treaters.

Referring to Figs. 1 and 2 a brief description of the operation and apparatus follows.

The apparatus comprises the following parts:

A high voltage transformer 1, high voltage electrical capacitances or condensers 2 and 2', resistance or impedance 3, rotary switch or interrupter rotor 4, with rotating conducting segments 5 and 6, stationary contact points 7, 8, 8' and 9, connecting conductors 10, 11, 12 and 13, switch 20, electrode 14, metallic shell 15 of the emulsion treater 16, electrode lead-in insulator 17, and emulsion treater inlets and outlets 18 and 19 respectively.

One method of operation is as follows:

Rotor 4 is mounted on the shaft of a synchronous motor and rotated at a speed which is in synchronism with the alternating high potential output of the transformer 1. Rotor 4 is thus

rotated so that at the time when the transformer output potential is at or near its maximum, segment 5 will be moving through the position shown in Fig. 1, completing the circuit between stationary points 8 and 9, thereby connecting the condenser 2 to the transformer. The circuit thus completed extends from the transformer 1 through the conductor 11, impedance or resistance 3, point 9, rotor segment 5, point 8, condenser 2 and conductor 10 back to the transformer. At this instant condenser 2 receives a full electrical charge at the transformer potential. During this charging period the circuit from condenser 2 to the treater 16 is open, as shown in Fig. 1, there being no segment in position to bridge the gap between points 7 and 8 in said circuit.

Immediately after the condenser 2 receives its charge, as explained above, the rapid rotation of rotor 4 carries segment 5 around to the position shown in Fig. 2, opening the circuit between the points 8 and 9, thereby disconnecting condenser 2 from transformer 1, and closing the circuit between points 7 and 8, connecting the condenser 25 across the treater electrodes. The condenser potential is then placed across the emulsion between electrode 14 and metallic treater shell 15, and the condenser charge is rapidly discharged therethrough by way of the completed circuit, point 8, segment 5, point 7, conductor 12, treater shell 15, electrode 14 and conductor 13.

As the rotor turns in synchronism with the alternating transformer output potential, the condenser is thus repeatedly and alternately connected to the transformer to receive a charge, then disconnected therefrom and connected to the treater through which it discharges the previously received charge. At no time is the transformer directly connected to the treater, for the treater receives its current only from the condenser discharge. Therefore the maximum possible demand upon the transformer is that which is required to completely charge condenser 2, regardless of what the conductivity of the material in the treater may be. Since the transformer is never in direct electrical connection with the treater, there can be no heavy current from the transformer following a short circuit between the electrodes.

50 The rapidity of discharge of the condenser through the treater and the value of the discharging current will depend largely upon the resistance of the emulsion between the electrodes. Since a condenser is capable of delivering a very heavy current for a limited time interval, it is therefore possible with this system to maintain momentarily a high potential difference across a low resistance path such as a highly conducting emulsion. This potential can be applied repeatedly and at as rapid frequency as is necessary to accomplish thorough treatment of the low resistant emulsion with the apparatus of this invention, whereas with the usual arrangement with the transformer directly connected to the treater, the voltage is reduced to an ineffectual value and remains such as long as the low resistant emulsion remains in the treating zone.

By choice of design of the interrupter 4 and the value of resistance or impedance 3, the period 70 of charging the condenser 2, from transformer 1, may be made relatively long as compared to the time of its discharge through emulsions of low resistance, thereby relieving the transformer of sudden charging shocks and lowering the accompanying power output peak. For example,

by lengthening the contact points of the charging contacts 8 and 9 and increasing the impedance of the charging circuit, as by impedance 3, the rate of charging of condenser 2 may be retarded. The rate of discharge of condenser 2 will be governed largely by the resistance of the emulsion in the treating space between the electrodes. 5

Rotor 4 may be run at synchronous speed under which condition the condenser 2 will be charged and discharged twice per cycle, each 10 charge at opposite polarity from the preceding one. This method of operation will be satisfactory, provided that the condenser is completely discharged through the treater with each connection therewith. If the resistance of the 15 emulsion in the treater is such, however, that a residual charge is left in the condenser following each discharge connection, it may result in an excessive peak charging current being drawn from the transformer and excessive sparking at 20 the contacts. When this condition prevails a preferred method of operation is to run the rotor at one half synchronous speed whereupon the contacts are always made with the condenser charging potential at the same polarity, allowing the condenser 2 to be charged only unidirectionally. Under this latter condition only one half of each cycle of the transformer output is utilized in charging condenser 2. By closing switch 20, a second condenser 2' may be connected, as shown on Fig. 1, to enable both sides of the alternating cycle of the transformer output to be utilized, while at the same time charging each condenser unidirectionally. 30

With the rotor running at one half synchronous speed, and with the switch 20 open as shown in Fig. 1, an interrupted direct current is supplied to the treater. With the rotor running at synchronous speed with the same connections, an interrupted alternating current is supplied 40 to the treater or the same is obtained by closing switch 20 when the rotor is run at one half synchronous speed. Variations of the above current supply characteristics may be obtained by running the rotor at multiples of the synchronous 45 speed with proper accompanying manipulation of switch 20; or the rotor may be run non-synchronously, producing an interrupted current of random polarity. Thus the electrical supply may be adapted to produce an output of a character best suited to the efficient treatment of the emulsion at hand. 50

Fig. 3 diagrammatically illustrates a method operating according to the principle outlined in connection with Fig. 1, whereby a number of individual treaters or a number of different pairs of electrodes in a treater can be operated, each treater or pair of electrodes receiving intermittent and successive electrical discharges. The operation of the system shown in Fig. 3 is as follows: 60

With the rotor in the position as shown in Fig. 3, condenser 22 receives a charge from transformer 21 by way of conductor 33, resistance or impedance 34, contact point 29, rotor segment 36, 65 contact point 25 and return line 35. The contact points are of sufficient size to permit complete charging and discharging of the condensers. The next position of the segment 36 following the one illustrated here, as the rotor 24 revolves 70 clockwise at one half synchronous speed, is that which bridges the gap between contact points 26 and 30. As this gap between 26 and 30 is bridged by segment 36, condenser 22 discharges the previously obtained charge through treater 75

42 by way of conductors 37 and 38. Following this, contact points 27 and 31 are closed by the segment 36 whereupon condenser 23 receives a charge from the transformer 21, which charge is immediately thereafter discharged through treater 41 by way of completing circuit conductors 43, 44 and 38, when contact points 28 and 32 are bridged; and so on, the condensers alternately receiving charges and discharging through the treaters.

Connection line 39 with switch 40 illustrates an optional connection between condensers 22 and 23 whereby they may be made to operate in parallel, in which case the condensers will be simultaneously charged and discharged in alternating polarity. Without connection 39, condensers 22 and 23 will operate independently without alternation of polarity of charge, i. e., each condenser will be charged unidirectionally.

Other arrangements are obvious to one skilled in the art, by which a plurality of treaters can be operated in a manner similar to that described above.

The treater 15, diagrammatically illustrated in Fig. 1 may be one of innumerable types suited to the treatment of emulsions. For purposes of illustration the one shown in Fig. 1 is of the pressure type in which the electrical treating field is maintained between electrode 14 and the treater shell 15. The emulsion enters the treater through 18, flows down through the treating zone between electrode 14 and shell 15, and out through outlet 19, to a tank where separate settling and separation of the emulsion phases is allowed to take place.

High voltage transformer 1 may be of any suitable voltage and power rating.

Condenser 2 may be of any suitable type, preferably with a capacity such that, at the frequency of charging, the maximum average charging power will be not greater than the desired output of the transformer.

The interrupter 4 may be of the synchronous rectifier type. This type of rectifier usually takes the form of a plurality of stationary electrodes or contact points circumferentially arranged with a plurality of points rotatably mounted to move past the said stationary points. The rotatable points are suitably arranged and connected together by interconducting bars, to accomplish, when rotated, the proper switching of circuits

terminating at the stationary points. These points—the rotatable and stationary ones—do not usually make mechanical contact, but for high voltage systems such as the one of this invention, merely pass one another with such slight clearance that the voltage therebetween is able to bridge the slight gap.

It is to be understood that the foregoing is merely illustrative of one apparatus and method of operation and that the invention is not limited thereby, but may include any method and apparatus to accomplish the same within the scope of the invention.

I claim as my invention:

1. A method of treating emulsions which comprises charging a plurality of condensers successively and discharging said charged condensers successively through a pair of electrodes in contact with emulsion to be treated, each condenser being isolated from the charging source during the discharging interval.

2. A method of treating emulsions which comprises charging a plurality of condensers successively and discharging said charged condensers successively each through a separate pair of a plurality of pairs of electrodes in contact with emulsion to be treated, each condenser being electrically isolated from the charging source during the discharging interval.

3. An apparatus for treating emulsions comprising a plurality of pairs of electrodes in emulsion to be treated, a source of high potential electricity, an electrical condenser system, and distributor means for alternately connecting said condenser system successively to said high potential source and to each pair of said electrodes in turn.

4. In a dehydrator having electrodes, a source of high voltage electrical energy, a plurality of condensers for storing said energy, and means for alternately connecting each of said condensers to said electrodes and to said source, said means being adapted to alternately disconnect each of said condensers from said source and connect each of said condensers to the electrodes whereby, when one of said condensers is connected to said electrodes and disconnected from said source, another of said condensers is disconnected from the electrodes and is connected to said source.

LYLE DILLON.
